UNITED STATES PATENT OFFICE.

JESSE A. B. SMITH, OF STAMFORD, CONNECTICUT, ASSIGNOR TO UNDERWOOD TYPE-
WRITER COMPANY, OF NEW YORK, N. Y., A CORPORATION OF DELAWARE.

TYPEWRITING MACHINE.

Application filed June 10, 1921. Serial No. 476,422.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to sheet-collating means, in which a statement-sheet and a ledger-sheet may be positioned relatively to a record-sheet. The data typed upon a number of statement-sheets and ledger-sheets are recorded upon a single record-sheet, the 10 latter remaining in the machine, while the successive statement-sheets and ledger-sheets for the individual customers are inserted in front of the record-sheet. Since the record-sheet is of considerable length so as to obstruct access to the rear of the platen, and the amount of typing on the statement-sheets and ledger-sheets is comparatively small, it is undesirable to insert the statement-sheets and ledger-sheets from the rear. 15 They are therefore inserted from the front of the machine, the usual feed-rolls having previously been cast off, and auxiliary feed-rolls being provided for holding the record-sheet in position while the statement-sheets 20 and ledger-sheets are adjusted in position. To aid in adjusting the sheets inserted at the front of the machine, there is provided a collating table at the front of the platen provided with left and right side edge gages. 25 The present invention contemplates the insertion of the statement-sheets and ledger-sheets at the front of the machine from the right-hand side when the typewriter carriage has been returned to the right, so that 30 the sheets may be in position for typing as soon as they are adjusted relatively to the record-sheet without further setting of the carriage. To aid in inserting these sheets from the right, there is provided a guard 35 on the right-hand end of the main frame of the typewriting machine to facilitate the passage of the sheets between the platen and the usual paper-apron. When the statement sheet and ledger-sheet have been inserted around the platen, they are adjusted with their left edges against the left side edge gage of the collating table. The ledger-sheet, which is usually wider than the statement-sheet, projects some distance to 40 the right beyond the latter, and has hitherto

been clamped by a clamp mounted adjacent the right side edge of the collating table, said clamp gripping the portion of the ledger-sheet which projects beyond the statement-sheet and leaving the latter free to be 45 adjusted relatively to the ledger-sheet and record-sheet.

It has been found, however, that the clamp, which has hitherto been pivotally mounted adjacent the right side edge gage 50 of the collating table, and which was swung outwardly to ineffective position when it was not desired to clamp the ledger-sheet, tended in some instances to obstruct the insertion of the statement-sheets and ledger-sheets 55 when they were inserted from the right. Also, it was not feasible to mount a clamp of this type adjacent the left side edge gage of the collating table, because the statement-sheet was gaged against the same side edge 60 gage as the ledger-sheet, and therefore lay directly over the ledger-sheet, so that when the clamp was swung outwardly to ineffective position, it would tend to tear the overlying statement-sheet, and the latter would 65 obstruct the movement of the clamp.

The present invention, therefore, provides a clamp which may be mounted adjacent the left side edge gage of the collating table to permit the statement-sheets and ledger-sheets to be inserted from the right without encountering obstructions, and to clamp the ledger-sheet in position beneath the statement-sheet, said clamp being so constructed that it may be released without being obstructed by the statement-sheet or tending to tear the latter. For this purpose, the clamp comprises a jaw movable toward and from the table and constantly parallel thereto, and beneath which the ledger-sheet is 70 clamped after being adjusted relatively to the record-sheet, the statement-sheet passing over said jaw. The clamp is so constructed that both sheets may be freely adjusted against the same side edge gage, and the operative jaw of said clamp may be released from contact with the ledger-sheet, said jaw moving at right angles to the collating table. The clamping jaw moves but a short distance sufficient to release the ledger-sheet, 75 but remains between the ledger-sheet and statement-sheet while said sheets are fed forwardly in the typing operation.

The type of clamp herein described is particularly desirable when the upper sheets 80

of a number of superposed sheets on the collating table extend beyond the clamps which hold the under sheets. Where swinging clamps were employed, it was difficult or awkward to clamp upper sheets at points beyond the clips which held the lower sheets, for the upper sheets would then prevent or interfere with the swinging of the clamps to ineffective positions. With the clamp used in the present invention, the lower sheets may be laid beneath the clamping jaw to be clamped thereby, while the upper sheets are passed over the clamping jaw and clamped at a point above the first clamp. Of these upper sheets, it is possible to lay certain of the lower ones beneath the clamping jaw of the second clamp and pass the upper sheets above this jaw to be clamped by a third clamp above the second. It will thus be seen that with this type of clamp, a number of superposed sheets may be clamped anywhere on the collating table, above or below the point at which an underlying sheet is clamped, for, when the clamps are released, the jaws are raised slightly to release the underlying sheets, said jaws remaining between the sheet below it and the sheet above it, and not interfering with the feeding of the sheets.

Other features and advantages will hereinafter appear.

In the accompanying drawings,

Figure 1 is a front view of the carriage of an Underwood standard typewriting machine with the invention applied thereto, the position of the record-sheet, ledger-sheet, and statement-sheet being indicated in dot-and-dash lines.

Figure 2 is a vertical section, taken on the line 2--2 of Figure 1, through the clamp as applied to the collating table, the clamp being shown in ineffective, or open, position.

Figure 3 is a view similar to Figure 2, but showing the clamp in closed or effective position.

Figure 4 is a vertical section of the device shown in Figure 1.

Figure 5 is a perspective view of the clamp applied to the table, and showing the method of adjusting the sheets with respect thereto.

Figure 6 is a detail perspective view showing the means for holding the auxiliary feed-rolls in ineffective position.

A platen 10 is fixed upon a shaft or axle 11, journaled in the end walls 12 of a platen-frame 13, which comprises a usual rear paper-table 15 provided with a forward extension or paper-apron 16 having openings 17 through which project front and rear feed-rolls 18 and 19 for holding work-sheets against the platen, and which may be thrown off in the usual way by the feed-roll-release handle 19. With the feed-rolls thrown off, a work-sheet, such as a record-sheet 20, may

be passed down the rear paper-table and around the platen to the printing point, indicated by the type-head 21, and held in position by auxiliary feed-rolls 26 mounted upon a shaft 27 journaled in bearings 28 on the end walls 12, said shaft being operated by a finger-piece 29 to swing said auxiliary rolls to effective or ineffective position. The auxiliary rolls are ordinarily held in effective position by springs 30 fixed to the shaft and to the bearings 28, but the rolls may be held in ineffective position by swinging the finger-piece 29 rearwardly where it is held by a spring detent 31 (Figure 6) mounted on the platen-frame. To release the finger-piece 29, the spring detent 31 need only be moved to one side to allow the finger-piece to move forwardly and swing the rolls 26 to effective position. When the work-sheet is adjusted in position and held by the auxiliary rolls, a statement-sheet and a ledger-sheet, together with their associated carbon-sheets, may be inserted from the front of the machine between the paper-apron and the platen, and may be guided between said apron and platen by a guard or guide 25 fixed to the main frame of the typewriting machine and projecting forwardly to co-operate with the forward edge of the paper-apron, said guard being more fully described in my co-pending application Serial No. 405,013, filed August 21, 1920 (now Patent No. 1,489,224, dated April 1, 1924).

With the carriage moved to a position substantially at the extreme right, as shown in Figure 1, the statement-sheet 35 and ledger-sheet 36, with their associated carbon-sheets, are swung downwardly from the extreme right, in front of guard 25, toward the left, and are adjusted in position on a collating table 37. Said table comprises two portions 38 and 39 mounted for lateral adjustment, preferably by countersunk screws 40, upon a bar 41 fixed to a frame 42, which is mounted by cross-bars 43 and 44 in the end-walls 12 and in end members 45 mounted on said end walls, respectively. The record-sheet 20 may be guided to the rear below the collating table by means of a spring finger 50 mounted on shaft 27, said finger conforming to the curvature of the platen, and therefore not interfering with the overlying statement and ledger-sheets.

When the statement and ledger-sheets have been inserted in the machine, they are then collated upon the table 37 with respect to the record-sheet and to each other. Both sheets are gaged against a left side edge gage 51 on the collating table, the ledger-sheet 36 being inserted beneath a jaw 52 of a clamp 53 mounted adjacent said left side edge gage, while the statement-sheet 35 is passed over said jaw. By thus mounting the clamp adjacent the left side edge gage,

the statement-sheet and ledger-sheet may be swung downwardly at the right without encountering projections on the right-hand side of the collating table due to the clamp.

- 5 The jaw 52 comprises a flat strip which lies parallel to the table 37 and forms one branch of a spring 54, the other branch 55 of said spring contacting with the under side of table 37 to which it is fixed, as by 10 rivets 61 (Figure 2). A reinforcing plate 56 is provided for the spring 54. For operating said jaw 52 to clamp or release an underlying sheet, there is provided a finger-piece 58 pivotally mounted in the upstanding 15 arms 62 of a U-shaped bracket 57 comprising the plate 56 fixed to the under side of the collating table, preferably by the same rivets 61 passing through branch 55 of the clamp, said finger-piece having cam-surfaces 59 and 60 for clamping and releasing the jaw 52. When the ledger-sheet 36 is properly adjusted beneath jaw 52, finger-piece 58 is swung upwardly to cause cam-surface 60 to contact with said jaw and 20 move the latter downwardly to effective position, and thus grip the ledger-sheet (Figure 3). The portion 39 may be adjusted so that the right side edge of the ledger-sheet, which extends beyond the statement-sheet, 25 may be gaged against gage 49 as well as gage 51. The overlying statement-sheet 35 is then adjusted in position beneath extensions 63 of the bracket 57 which prevents said sheet from falling forward, whereupon 30 the feed-rolls 17 and 18 are applied to all the sheets, and the clamp 53 is released by swinging finger-piece 58 downwardly to bring cam-surface 59 in contact with jaw 52, so that said jaw may spring upwardly 35 a short distance sufficient to release the ledger-sheet, the jaw 52 remaining between the ledger-sheet and the statement-sheet, and lying parallel to said sheets.

The jaw 52 in released position, therefore, 40 does not interfere with the forward feeding of the statement-sheet and ledger-sheet. This construction differs from clamps hitherto used, in which the clamping jaws, corresponding in function to jaw 52, swung outwardly about pivots so that the overlying sheets would interfere with their movement, or else these sheets would be torn by the clamps in their outward movement. The work-sheets may be aligned by means 45 of the edges 65 of the usual wing-scales 66.

Variations may be resorted to within the scope of the invention, and portions of the improvements may be used without others.

Having thus described my invention, I 50 claim:

1. In a typewriting machine, a platen, a collating table at the front of the platen upon which work-sheets may be adjusted, a clamp formed to be interposed between work-sheets on the collating table for clamp-

ing one of them by a lateral margin, said clamp being movable slightly toward and from the collating table while remaining about parallel therewith, and a single side-edge gage on the collating table extending above and below said clamp, and gaging the sheets placed upon and underneath the clamp.

2. In a typewriting machine, a platen, a collating table at the front of the platen, an edge gage upon the collating table, means for clamping a work-sheet against the collating table, comprising a thin blade-like clamping jaw which passes through the edge gage and has a smooth upper face to permit the unobstructed passage of work-sheets thereover, and means for causing the clamping jaw to move through a limited range toward and from the collating table in substantially fixed angular relationship thereto.

3. In a typewriting machine, a platen, a collating table at the front of the platen, an edge gage upon the collating table, means for clamping a work-sheet against the collating table, comprising a thin blade-like clamping jaw mounted outside the edge gage and passing therethrough, said clamping jaw having a smooth upper surface to permit the unobstructed passage of work-sheets thereover, and a cam-lever mounted on the collating table adjacent the edge gage for controlling the clamping jaw to move it to clamping position and to limit its movement away from clamping position to prevent its being moved more than the distance necessary to withdraw its clamping face from contact with the work.

4. In a typewriting machine, a platen, a collating table at the front of the platen upon which work-sheets may be adjusted, an edge gage on the collating table, a paper-clamping jaw movable through said gage, and means for constraining the jaw to move toward and from the collating table in substantially fixed angular relationship thereto.

5. In a typewriting machine, a platen, a collating table at the front of the platen upon which work-sheets may be adjusted, a clamping jaw movable toward and from the collating table, resilient means urging the clamping jaw away from the collating table, and a cam-lever pivoted on the collating table for moving the jaw to effective position, having a handle and having two flat surfaces located at different distances from its pivot for engaging the jaw to retain it in its effective position and in its ineffective position.

6. In a typewriting machine, a platen, a collating table at the front of the platen upon which work-sheets may be adjusted, an edge gage at the side of the collating table, a clamp comprising a spring clip having upper and lower substantially parallel legs

and an enlarged resilient loop portion connecting them, the lower leg of the clip being rigidly secured to the collating table in a position such that the resilient loop portion will be located beyond the lateral edge of the collating table and the upper leg will be positioned above the collating table and will pass through the edge gage, and means mounted on the collating table, just outside the edge gage, for engaging the upper leg of the clip and movable in one direction to force said leg to clamping relationship with the table, and in the other direction to permit the upper leg of the clip to rise a short distance to release the paper on the collating table.

7. In a typewriting machine, the combination with a platen around which sheets are fed, of a collating table at the front of the platen and upon which sheets are adjusted, and means for clamping said sheets to said table, said means comprising a clip having one branch fixed to the table and the other branch forming a clamping jaw extending above said table and parallel thereto, and means for moving said jaw downwardly to clamp said sheets to said table.

8. In a typewriting machine, the combination with a platen around which sheets are fed, of a collating table at the front of the platen and upon which sheets are adjusted, and means for clamping said sheets to said table, said means comprising a clip having one branch fixed to the table and the other branch forming a clamping jaw extending above said table and parallel thereto, and a cam member pivotally mounted adjacent said clip for moving said jaw downwardly to clamp said sheets to said table.

9. In a typewriting machine, the combination with a platen around which sheets are fed, of a collating table at the front of the platen and upon which sheets are adjusted, and means for clamping said sheets against said table, said means comprising a spring clip having one branch fixed to said table and the other branch forming a clamping jaw extending above said table and parallel thereto, and a cam member pivotally mounted adjacent said clip, said cam member having a cam surface for contacting with said jaw to move the latter downwardly to clamp said sheets to said table, said cam member having a second cam surface for permitting said jaw to spring upwardly out of contact with said table to release the sheets.

10. In a typewriting machine, the combination with a platen around which a plurality of superposed sheets are fed, of a collating table at the front of the platen and upon which sheets are adjusted, said table having a side edge gage, a clamp mounted on said table adjacent said side edge gage and having a jaw projecting inwardly par-

allel to the table, so that sheets may pass above and below the jaw, the remainder of the clamp exclusive of said jaw being mounted outside of the side edge gage, so that all of said sheets may be gaged against side edge gage without being obstructed by the clamp, and means for moving said jaw downwardly to clamp to said table the sheets lying beneath the jaw.

11. In a typewriting machine, the combination with a platen around which a plurality of superposed sheets are fed, of a collating table at the front of the platen and upon which sheets are adjusted, said table having a side edge gage, a clamp mounted on said table adjacent said side edge gage and having a jaw projecting inwardly parallel to the table, so that sheets may pass above and below the jaw, the remainder of the clamp exclusive of said jaw being mounted outside of the side edge gage, so that all of said sheets may be gaged against said side edge gage without being obstructed by the clamp, means for moving said jaw downwardly to clamp to said table the sheets lying beneath the jaw, and means whereby said jaw may move upwardly to release the underlying sheets, said jaw remaining between the lower and upper sheets during the feeding of said sheets.

12. In a typewriting machine, in combination, a platen, a paper-table at the rear of the platen for guiding a wide sheet to the platen, a collating table at the front of the platen for receiving a narrower sheet, a rotatable shaft, means carried by said shaft for directing said wide sheet between the lower edge of the collating table and the platen, and means connected to the shaft for constantly urging the shaft in a direction to render said directing means effective, said shaft being rotatable against the action of said last-named means to render the directing means ineffective, and means for holding said shaft in ineffective position.

13. In a typewriting machine, in combination, a platen, a paper-table at the rear of the platen for guiding a wide sheet to the platen, a collating table at the front of the platen for receiving a narrower sheet, a rotatable shaft, means carried by said shaft for directing said wide sheet between the lower edge of the collating table and the platen, means connected to the shaft for constantly urging the shaft in a direction to render said directing means effective, said shaft being rotatable against the action of said last-named means to render the directing means ineffective, and means for holding said shaft in ineffective position, said last-named means comprising a spring catch and a handle fixed to said shaft and engageable by said spring catch when the shaft is rotated in a direction to render the directing means ineffective.

14. In a typewriting machine, a platen, feed-rolls co-operating therewith, a front insertion guide for work-sheets at one end portion of the platen, a front collating table having a side gage at the other end portion of the platen, and a clamp holding the underneath sheet stationary after its adjustment and during the adjustment of the outer sheet, the clamp comprising a blade-like jaw 10 and means controlling the jaw to cause it to move through a narrow range and always in substantially parallel relation to the collating table, the clamp being releasable without disturbing the outer sheet, and permitting the sheets to be line-fed together.

15. In a typewriting machine, a platen, a front insertion guide at one end portion of

the platen, a front collating table having a side gage at the other end portion of the platen, and a clamp clamping the inner 20 sheet after it has been adjusted and during adjustment of the outer sheet, said clamp comprising a short blade-like clamping jaw movable slightly between its clamping position and its ineffective position, being in 25 both positions substantially parallel to the collating table, permitting the inner and outer sheets to be gaged one below and one above the clamping jaw.
